BILLIARD CUE RACK

Samuel H. Berger, Skokie, Ill., assignor to Ajax Enterprises Corporation, Delavan, Wis.

Filed Feb. 27, 1970, Ser. No. 21,659

Term of patent 14 years

Int. Cl. D6—99

U.S. Cl. D33—3

FIG. 1 is a perspective view of a billiard cue rack showing my new design;

FIG. 2 is a side elevational view thereof, the opposite side being substantially the same;

FIG. 3 is a top plan view thereof; and

FIG. 4 is a bottom plan view thereof.

I claim:

The ornamental design for a billiard cue rack, as shown and described.
